MACHINE FOR SHAPING SHOES

Arthur F. Pym, Swampscott, and Joseph W. Johnson, Beverly, Mass., assignors to United Shoe Machinery Corporation, Paterson, N. J., a corporation of New Jersey

Application May 2, 1930. Serial No. 449,312

35 Claims. (Cl. 12—51)

This invention relates to machines for shaping shoes and is herein illustrated as embodied in a machine adapted particularly for use in shaping turn shoes after the shoe-turning and relasting operations have been performed.

The operations referred to leave the shoe upper in a more or less distorted condition with the result that it is necessary to shape and to smooth it in order to bring the upper into conformity with the shape of the last, particularly along the side edge portions thereof, thereby to impart to the upper a finished appearance.

An object of the present invention is to provide an improved machine for shaping the uppers of shoes which will be adapted for performing the upper-shaping operation referred to and which, while retaining all the advantages of machines for performing that operation as heretofore constructed, will be especially effective to shape the shoe upper closely to the last, will be rapid in its operation, and will be so constructed that it will not require great attention on the part of the operator. As illustrated, the invention provides, in a machine of the type referred to, a plurality of beating tools arranged for operation upon opposite sides of the upper of a shoe, the tools being mounted for rotation about axes extending in directions at right angles to each other so that the faces of the tools will accommodate themselves to the shape of the last of the shoe presented between the tools. Preferably, the tools are mounted in supporting members capable of movement toward and away from each other to provide for the insertion of the forepart of the shoe between the tools and to permit its movement past the tools. The illustrated tools are operated by oscillating hammers effective to operate the tools in any angular position, the mounting of the tools being such that blows delivered by them upon the work will be delivered substantially normally thereto. Preferably, the lower portion of each tool is provided with a lip for engaging the crease between the sole and upper of the shoe for the purpose of guiding the shoe as it is advanced past the tool. Preferably too, the tools are forced into engagement with the upper of a shoe under spring pressure which is effective to hold the shoe in position on the tools with the result that the operator is required only to advance the shoe inwardly past the tools.

The illustrated construction is such that the tools operate upon the upper of a shoe presented between them progressively from the tip of the shoe rearwardly toward the ball-line thereof.

The beating action of the tools upon the upper shapes it to the last along the side edge portions of the last, giving it a finished appearance.

Other objects and features of the invention will be apparent from the following detailed description when taken in connection with the accompanying drawings, in which

Fig. 1 is a front elevation of portions of a machine embodying the invention;

Fig. 2 is a front view partly in section, illustrating details of the tool mounting and operating mechanism; and

Fig. 3 is a horizontal sectional view taken along line III—III of Fig. 1.

The machine comprises beating tools 10 and 11 arranged for operation upon the opposite sides of the uppers of shoes, such as a shoe 12. The tools 10 and 11 are positioned in holders 14 and 15 which are mounted for reciprocating movement in heads 16 which are carried by brackets 18. The brackets 18 are pivoted respectively to supporting members or brackets 20 and 21 in such a manner that the tool holders 14 and 15 and consequently the tools 10 and 11 can be rotated about vertical axes in conforming to the surfaces of the shoe upon which they operate. Carried by the supporting members 20 and 21 are hammers 22 which operate to produce beating action of the tools upon the work. The members 20 and 21 are connected to a frame 24 of the machine by links 26, the construction being such that each of the members and the mechanisms associated therewith, including the tools, depend from the frame, the members being movable toward and away from each other so that the tools carried thereby can be separated to permit the insertion between them of a shoe to be operated upon.

The tools 10 and 11 and their associated mechanisms are substantially identical in construction, and consequently only the tool 10 and the parts associated with it, which are shown in the left-hand portion of Fig. 1, will be described in detail.

The tool 10 (Fig. 1) is provided with a curved face 28 which corresponds substantially to the contour of the lower portion of the upper of a shoe adjacent to the sole, the lower portion of the tool being provided with a lip 30 adapted for insertion in the crease between the upper and the sole of a shoe and operable when the tool is oscillated to shape the upper to the last in conforming the upper to the side edge portions of the last. The tool 10 has a rear part 32 positioned in a curved slot 34 in the tool holder 14,

said rear part having circular grooves 36 in the side walls thereof which are engaged by pins 38 located in opposite walls of the tool holder. The construction just described is such that the tool 5 can be rotated in a holder in a vertical plane about an axis substantially at the centers of curvature of the grooves 36 thus to provide for rotation of the tool face to accommodate it to the surface of the upper being operated upon.

10 For urging the tool into the crease of the shoe there is provided a spring 40 secured to the tool holder by a pin 42 and to the tool by a pin 44, the spring being under tension along a line which passes above the axis of the curved grooves 36 15 with the result that the spring tends to rotate the tool in a downward direction thus to force the lip 30 downwardly and inwardly into the crease. Downward movement of the tool is limited by means of a plate 46 secured to the tool at the top thereof by screws 48. One end of the plate 46 projects beyond the rearward portion of the tool and in the lowermost position of the tool engages the upper surface of the tool holder 14 which thus acts as a stop.

20 The tool holder 14 is pivoted on a pin 50 located in a carrier 52, the axis of the pin being substantially parallel to the lip 30 of the tool. The carrier 52 has located in it a plunger 54 (Fig. 3) which at its outer end makes connection with the tool holder 14 by a link 56, the plunger normally being forced outwardly by a spring 58. The purpose of this construction is to provide yieldable mounting for the tool holder 14 operative to force the tool inwardly into the crease of the shoe as the shoe is initially presented to the tool.

25 The tool carrier 52 which is slidably mounted in the head 16 is arranged for sliding movement at right angles to the head and can be adjusted laterally of the head. This adjustment is provided for by bearing plates 60, located on each side of the carrier, said plates being forced inwardly against the side walls of the carrier by spring-pressed plungers 62 which are located in blocks 64 slidable in the head 16. The rear surface of each of these blocks is curved and makes contact with a cylindrical stop 66 which is movable laterally in the head. Adjustment of the bearing plates 60 is made by moving the stops 66 inwardly or outwardly, each of the stops being held in the adjusted position by a bolt 68 which can be turned to force a collar 70 carried by the bolt against the side wall of the head thus to hold the stop in fixed position. The bearing plates 60 are so adjusted that the pressure upon the side walls of the carrier 52 will hold the carrier in substantially fixed position centrally of the head 16 but will, however, permit a small amount of play laterally which will further assist the tool in accommodating itself to the curvature of the upper of the shoe being operated upon.

30 On the side of the carrier 52 opposite to that upon which is secured the tool holder there is located a plate 72 secured to the carrier by screws 74. The inner wall of this plate is spaced from the head 16 by spring-pressed plungers 76 which normally operate to force the carrier in a direction away from a shoe in operative position relatively to the tool, outward movement of the carrier being limited by an abutment 77 which 35 engages the side of the head 16. The outer wall of the plate 72 has a curved face 78 arranged to be engaged by the oscillating hammer 22, operative intermittently to force the plate 72, and consequently the carrier 52, inwardly, the carrier 40 being moved in the opposite direction by the 45 plungers 76 after each blow of the hammer.

50 The head 16 is mounted upon a pair of vertically extending rods 80 which form a part of the bracket 18, the head being capable of movement in a vertical direction along the rods but being normally held in substantially fixed position against collars 82, secured upon the rods, by springs 84 which force the head upwardly. The springs 84 take the downward thrust of the carrier as the tools are forced against the work. The bracket 18 comprises oppositely disposed V-shaped arms 86 secured to the upper and lower ends respectively of the rods 80, said arms being pivotally secured to upper and lower extensions 88 of the bracket 20, each of the arms 86 being provided with a pivot pin 90 (Fig. 2) supported in the extensions 88 by anti-friction bearings 92. It should be noted that a line coinciding with the axes of the pivots passes substantially through the central portion of the lip 95 of the tool 10 so that the tool face when rotated with the bracket 18 around the pivots will always be positioned substantially parallel to the upper of a shoe located between the tools 10 and 11. Furthermore, it will be seen that the tool faces, as 100 they are reciprocated toward and from the work, will move in a direction substantially at right angles to the upper of the shoe being operated upon.

105 To provide for the insertion of a shoe between the tools 10 and 11, the members 20 and 21 which indirectly support the tools are arranged for movement outwardly. To this end, the upper portion of each of the members is provided with a pair of plates 94 through which extend pivot pins 96 forming connections with links 26. The upper ends of the links 26 are in turn mounted upon pivots 98 carried by the frame 24. The links 26 are of the same length and, consequently, movement of the links about the pivots 110 98 will result in straight-line movement of the members 20 and 21, and the parts carried by the members will remain in the same relative vertical positions. In view of the fact that the outward movement of the members required to permit the insertion of a shoe 12 between the tools is small as compared with the lengths of the links, the upward movement of the members and, consequently, of the tools will be so small that it will not affect the presentation of the work 115 to the tools.

120 In order to force the members 20 and 21 toward each other so that the tools 10 and 11 will be pressed firmly against the shoe upon opposite sides thereto, the members are connected by a spring 100 which normally operates to force the members inwardly until the links 26 are substantially vertical. In this position the distance between the tools is such that the toe of a shoe can be readily inserted between the tools, this 125 operation being facilitated by having the brackets 18 normally positioned so that the faces 28 of the tools diverge toward the front of the machine. To this end, the rearward portions of the brackets 18 are connected by a spring 102 normally operative to rotate them about their pivots 90 until the tool faces diverge sufficiently to 130 permit insertion between them of the forepart of a shoe.

135 It is to be noted that the spring 100 is sufficiently strong to force each of the tool holders, against the pressure of the spring 58, into engagement with the abutment 77 when a shoe is located between the tools 10 and 11, and to force the lips 30 of the tools inwardly with sufficient 140 force to hold the shoe in position.

145

pressure to support the shoe upon the tools. The hammer 22 which produces vibratory operations of the tool 10 comprises a substantially cylindrical body portion 104 which is hollowed out to reduce its weight and which has a head 106 provided with curved striking faces 107 adapted to engage the outer face of the plate 72 of the carrier 52 in any angular position thereof. The body portion 104 of the hammer is 10 slidably mounted in bearings 108 in the supporting member 20 and has an extension 110 which is slidable in bearings 112 carried by a plate 114 secured to the member 20 by rods 116. The hammer is normally forced inwardly toward plate 72 by means of a spring 118 which surrounds the extension 110. The outer portion of the extension 110 carries a fixed spring perch 120 and a loose collar 122 between which is located a stiff spring 124. The construction and arrangement of the parts just described are such that, when the hammer is forced inwardly by the spring 118 as it reaches the end of its stroke, the collar 122 will be brought into engagement with the outer surface of the bearing 112, and the spring 124 will then be effective to counteract pressure exerted by the spring 118, thereby cushioning the effect of the blow delivered by the hammer.

Outward movement of the hammer is effected by means of a cam 126 which engages the roll 128 carried by pin 130 secured to the hammer head 106. Rotation of the cam 126 results in the retraction of the hammer when the high part 132 of the cam engages the roll 128. Upon passing the high part 132 the spring 118 rapidly forces the hammer inwardly, thereby delivering a blow to the plate 72 of the carrier 52, which in turn slides in the head 16 and forces the tool 10 inwardly. In the operation of the machine the cam is rotated rapidly thereby to produce a rapid succession of blows.

The cam is rotated by a flexible shaft 134 the upper end of which is mounted in bearings 136 in the bracket 20. The lower portion of the shaft 134 extends through a gear case 138 carried by the frame, the shaft being provided with universal joints 140 and 142 whereby the shaft can be moved angularly at such times as the bracket 20 is moved laterally. A similar shaft 144 is provided for driving the corresponding cam 126 on the opposite side of the machine. Shafts 134 and 144 are driven in opposite directions from a main shaft 146 through a train of gears 148. The cams 126 are so timed that the hammers 22 will be operated in synchronism with the result that the blows of the hammers will effect a simultaneous pressing of the tools 10 and 11 against a shoe on opposite sides thereof so that the forces exerted upon the shoe will be compensated.

For operating upon the tip portions of shoes there is provided a tool 150 similar in construction to the tools 10 and 11 and similarly mounted in a tool holder 152 which is carried by a slide 154 mounted for vertical movement in the frame 65 of the machine. The slide 154 is reciprocated by a spring 156 and by cam-operated devices which are not shown but which are similar in construction to the mechanism for operating the hammers 22.

In the operation of the machine, a shoe, such as shoe 12, is presented bottom down between the tools 10 and 11 so that the lips 30 of the tools engage the upper of the shoe adjacent to the crease between the upper and the sole at points near the tip of the shoe, the tool holders 14 and

15 being tilted inwardly at this time, as shown in Fig. 2. The shoe is then pressed inwardly with the result that, as the tools successively engage wider portions of the forepart of the shoe, the tools and tool holders will be forced apart until the rear portion of each of the holders is in contact with the faces of the tool carriers 52. Further movement of the shoe inwardly will force apart the supporting members 20 and 21 against the tension of the spring 100, the brackets 18 being rotated upon their pivots 90 and the tools rotating upon their horizontal axes until the faces 28 of the tools conform closely to the shape of the last along the lower side edge portions thereof. As the shoe is advanced between the tools, the hammers 22 operate to deliver a succession of blows upon the carriers with the result that the tools are forced inwardly to press the upper firmly against the last, smoothing it and shaping it to the lower side edge portions of the last. Because of the resilient mounting of the tools the latter are moved slightly in a curved path during each pressure stroke, thereby producing a rubbing as well as a pounding or beating action upon the upper. As the shoe is advanced between the tools, the latter operate upon the upper progressively along the lower edge portions thereof from points at opposite sides of the shoe close to the tip thereof back to the ball-line. As the shoe is advanced, the brackets 18 rotate and members 20 move outwardly to accommodate the increased width of the shoe toward the rear thereof but always presenting the tools with their faces substantially parallel with the portions of the upper which they engage and with the application of pressure of the tools substantially at right angles to the upper.

Upon completion of the operation upon the side portions of the shoe, the latter is presented to the tool 150 which operates to beat that portion of the upper at the tip which is not acted upon by tools 10 and 11.

Having described our invention, what we claim as new and desire to secure by Letters Patent of the United States is:—

1. A machine for shaping shoes, comprising a plurality of tools arranged for operation upon opposite sides of the upper of a shoe positioned between the tools, means for forcing the tools toward the shoe to support it, and means for causing the tools to deliver blows in rapid succession in directions substantially normal to the upper of the shoe.

2. A machine for shaping shoes which have been turned and relasted, comprising a plurality of tools arranged for operation upon opposite sides of the upper of a lasted shoe along the side edge portions thereof, and means for causing the tools to deliver blows simultaneously upon opposite sides of the upper to shape the upper to the last.

3. A machine for shaping shoes which have been turned and relasted, comprising a plurality of tools arranged for operation upon opposite sides of the upper of a lasted shoe, mountings for the tools arranged to provide for angular movements of the tools in presenting operating faces thereof substantially parallel to the portions of the upper to be operated upon, means upon the tools for guiding the shoe as it is moved past the tools, and means for oscillating the tools in directions normal to the upper to shape the edge portions of the upper to the last.

4. A machine for shaping shoes, comprising a plurality of beating tools arranged for operation

- upon opposite sides of the upper of a shoe presented between the tools, means for mounting the tools for locating their faces substantially parallel to the portions of the upper which they engage, means for forcing the tools into the crease between the upper and the sole of the shoe to support the shoe and to guide it as it is moved past the tools. 5. A machine for shaping shoes, comprising a plurality of beating tools arranged for operation upon opposite sides of the upper of a shoe presented between the tools, means for directing the tools into the crease between the upper and the sole of the shoe, means for oscillating the tools, and means for forcing the tools toward each other to support the shoe during oscillation of the tools. 6. A machine for shaping shoes, comprising a plurality of tools operable upon opposite sides 10 of the upper of a shoe presented between the tools, means for mounting the tools to present the faces thereof substantially parallel to the portions of the upper which the tools engage, means for forcing the tools into the crease between the upper and the sole of the shoe to guide the shoe as it is moved past the tools, and means for causing oscillations of the tools to deliver a series of blows to the upper of the shoe substantially normally thereto. 7. A machine for shaping shoes, comprising a plurality of tools arranged for operation upon opposite sides of the upper of a lasted shoe presented between the tools, means for forcing the tools into the crease between the upper and the sole of the shoe for supporting the shoe and guiding it as it is advanced past the tools, mountings for the tools arranged to provide for angular movement of the tools in adjusting the faces of the tools to conform to the shape of the last as the shoe is moved progressively past the tools. 8. A machine for shaping shoes, comprising a plurality of tools arranged for operation upon opposite sides of a lasted shoe positioned between the tools, yieldable means for forcing the tools into engagement with the upper of the shoe along the crease between the upper and the sole thereof as the shoe is moved progressively past the tools, and yieldable mountings for the tools arranged to provide for angular movement of the tools in locating the faces of the tools substantially parallel to the upper in various positions. 9. A machine for shaping shoes, comprising a plurality of beating tools arranged for operation upon opposite sides of the upper of a shoe presented to the tools, mountings for the tools arranged to provide for angular movement of the tools in locating the faces thereof substantially parallel to the upper of the shoe as it is advanced past the tools, and means for initially positioning the tools with their faces outwardly disposed to facilitate presentation of the shoe to the tools. 10. A machine for shaping shoes, comprising a plurality of beating tools arranged for operation upon opposite sides of a lasted shoe positioned between the tools, pivotally mounted brackets, tool carriers positioned in the brackets and arranged for supporting each of the tools for angular movement about axes extending in directions at right angles to the axes of the brackets for locating the tools relatively to the shoe, and means for oscillating the tools as the shoe is moved relatively to the tools. 11. A machine for shaping shoes, comprising a plurality of beating tools for operating upon opposite sides of a shoe on a last positioned between the tools, brackets mounted for movement about vertical axes, tool carriers supported by the brackets and arranged for angular movement about horizontal axes for locating the tools with their faces substantially parallel to the side surfaces of the last, and supporting members for the brackets movable away from each other under pressure of the shoe as the shoe is moved past the tools. 12. A machine for shaping shoes, comprising a plurality of tools for operating upon opposite sides of the upper of a lasted shoe, brackets mounted for movement about a vertical axis, means carried by the brackets for supporting each of the tools for movement about a horizontal axis, means for forcing the tools toward the upper of the shoe as it is advanced between the tools, and means for oscillating the tools to deliver a succession of blows to the upper of the shoe. 13. A machine for operating upon shoes, comprising a frame, a pair of supporting members depending from the frame, a bracket mounted in each of the members and arranged for movement about a vertical axis, a carrier located therein and arranged for sliding movement laterally of the bracket, a beating tool positioned in each of the carriers, the construction and arrangement being such that the shoe presented between the tools will be effective to rotate the brackets about their vertical axes thereby to position the tools with their operative faces substantially parallel to the portions of the upper of the shoe which they engage. 14. A machine for shaping shoes, comprising a pair of beating tools for operation upon opposite sides of a shoe on a last and having faces curved to correspond to the shape of the last, brackets for supporting the tools movable bodily toward and away from each other and about vertical axes for presenting the tools with their faces substantially parallel to the upper of the shoe, and means for oscillating the tools in the brackets. 15. A machine for shaping shoes, comprising a frame, a supporting member movable laterally of the frame, a bracket carried by the supporting member and movable about a vertical axis, a beating tool mounted in the bracket for movement about a horizontal axis, and means for oscillating the tool relatively to the bracket. 16. A machine for shaping shoes, comprising a plurality of supporting members, a plurality of brackets each having a tool carrier slidably mounted therein, tools mounted in the carriers for movement about horizontal axes, and means for mounting the brackets in the supporting members for movement about a vertical axis for positioning the tools substantially parallel to the faces of a shoe presented between the tools. 17. A machine for shaping shoes, comprising a pair of beating tools arranged for operation upon opposite sides of a shoe presented to the tools, each of the tools being mounted for angular movement bodily about an axis passing through the operative face of the tool. 18. A machine for shaping shoes, comprising a frame, a pair of supporting members depending from the frame and mounted for movement toward and away from each other, brackets positioned in each of the supporting members, tool carriers positioned in the brackets, beating tools supported by the carriers and arranged for movement about vertical axes intersecting the faces of the tools, and reciprocating hammers carried by the brackets for operating the tools.

19. A machine for shaping shoes, comprising a frame, a pair of carriers slidably mounted relatively to the frame, beating tools mounted in the carriers for angular movement relatively thereto and having operative portions adapted to enter the crease between the upper and the sole at opposite sides of a shoe advanced between the tools, and means for rotating the tools in the carriers to force the tools into the crease thereby to guide the shoe as it is advanced between the tools.

20. A machine for shaping shoes, comprising a frame, a pair of carriers slidably mounted relatively to the frame, tool holders mounted in the carriers for angular movement relatively thereto, tools positioned in the tool holders and having operative portions arranged to enter the crease between the upper and the sole at opposite sides of a shoe advanced between the tools, means for rotating the tool holders in the carriers to force the tools into the crease thereby to guide the shoe as it is advanced past the faces of the tools, and means for oscillating the carriers to produce beating operations of the tools upon the upper of the shoe.

21. A machine for shaping shoes, comprising a plurality of tools for operating upon opposite sides of a lasted shoe, each of the tools having a lip adapted to enter the crease between the upper and the sole of a shoe positioned between the tools, means for forcing the tools toward each other with sufficient pressure to cause the lips of the tools to support the shoe, and means for oscillating the tools.

22. A machine for shaping shoes, comprising a plurality of beating tools for operating upon opposite sides of a lasted shoe, each of the tools having a lip adapted to enter the crease between the upper and the sole of a shoe positioned between the tools, supporting members for the tools movable toward and away from each other, and yieldable means for forcing the members toward each other with sufficient pressure to cause the lips of the tools to support the shoe.

23. A machine for shaping shoes, comprising a tool holder, a beating tool mounted for angular movement in the tool holder, said tool having an operating face curved to correspond to the curvature of the side edge portion of the last of a shoe to be operated upon and having a lip portion adapted to enter the crease between the upper and the sole of the shoe, means for moving the tool in a direction to force the lip of the tool into the crease and yieldable to provide for the conforming of the face of the tool to the last, and means for oscillating the tool holder to produce beating operations of the tool upon the upper of the shoe.

24. A machine for shaping shoes, comprising a tool carrier having an abutment, a tool holder mounted upon the carrier and movable relatively to the abutment, a beating tool positioned in the holder and having an operative portion adapted to enter the crease between the upper and the sole of a shoe presented to the tool to guide the shoe as it is advanced past the tool, means for holding the tool holder away from the abutment yieldable under pressure of the shoe against the tool, and means for oscillating the carrier to produce beating operations of the tool upon the shoe.

25. A machine for shaping shoes, comprising a tool having a curved face terminating in a lip portion adapted to enter the crease between the sole and the upper of a shoe to be operated upon, a tool holder, means on the tool co-operable with the tool holder to provide for movement of the

26. A machine for shaping shoes, comprising a tool about a horizontal axis, a mounting for the tool holder arranged for movement about a vertical axis passing through the face of the tool, the construction and arrangement being such that the face of the tool can be rotated into position closely to conform to the surface of the shoe upper which it engages, and means for causing the tool to deliver blows in rapid succession to the shoe upper.

27. A machine for shaping shoes, comprising a beating tool, a tool holder in which the tool is positioned, the holder having means for engaging the tool whereby the latter is movable about a horizontal axis, a carrier upon which the tool holder is pivoted, yielding means tending to rotate the tool about the axis, and yielding means tending to move the holder angularly of the carrier.

28. A machine for shaping shoes, comprising a beating tool, a tool carrier mounted for movement about a vertical axis passing through the face of the tool, a support for the carrier movable in a lateral direction, and a mounting for the tool arranged to provide for rotation of the tool about a horizontal axis.

29. A machine for operating upon shoes, comprising a beating tool, a carrier upon which the tool is supported, a bracket mounted for movement about a vertical axis and in which the carrier is slidably mounted, a supporting member for the bracket, and a reciprocating hammer mounted in the supporting member and operable to engage the carrier in producing operations of the beating tool.

30. A machine for shaping shoes, comprising a bracket mounted for rotation about a vertical axis, a carrier slidably mounted in the bracket, a beating tool mounted on the carrier, an oscillatory hammer mounted independently of the bracket and having a curved striking face, and a plate forming part of the carrier and having a curved face for engaging the face of the hammer in any angular position of the bracket.

31. A machine for shaping shoes, comprising a supporting member, a bracket pivotally mounted upon the supporting member, a tool carrier slidably mounted in the bracket and having a curved rear face, a beating tool mounted in the forward part of the carrier, and an oscillating hammer mounted in the supporting member and having a curved striking face for engaging the curved face of the carrier to actuate the tool.

32. A machine for shaping shoes, comprising a frame, a pair of supporting members depending from the frame, tools carried by the supporting members and arranged to engage opposite sides of a shoe positioned between the tools, means for mounting the supporting members for movement laterally of the frame under pressure of the shoe

as it is advanced between the tools, and means carried by the supporting members for reciprocating the tools.

33. A machine for shaping shoes, comprising a frame, a plurality of beating tools arranged for operation upon opposite sides of the upper of a shoe positioned between the tools, supporting members for the tools carried by the frame and movable toward and away from each other in presenting the tools to the shoe, means carried by the supporting members for oscillating the tools to cause them to deliver blows to the upper of the shoe, a drive shaft mounted in the frame, and operative connections between the oscillating means and the drive shaft movable angularly of the frame and of the supporting members.
34. A machine for shaping shoes, comprising a frame, a plurality of beating tools arranged for operation upon opposite sides of the upper of a shoe positioned between the tools, supporting members for the tools carried by the frame and movable toward and away from each other in

presenting the tools to the shoe, means carried by the supporting members for oscillating the tools to cause them to deliver blows to the upper of the shoe, and means for driving the oscillating means, said driving means being mounted in the frame for angular movement and being movable with the supporting members.

35. A machine for shaping shoes, comprising a frame, a pair of supporting members depending from the frame, tools carried by the supporting members and arranged to engage opposite sides of a shoe positioned between the tools, means for mounting the supporting members for movement laterally of the frame under pressure of the shoe as it is advanced between the tools, hammers carried by the supporting members for causing the tools to deliver a succession of blows to the shoe as the latter is advanced between the tools, and means comprising flexible shafts for oscillating the hammers.
